RECORD PLAYER PICK-UP CARTRIDGE

Norman Lane, Halesowen, England, assignor to BSR
Limited, Cradley Heath, Warley, England

Filed June 20, 1974, Ser. No. 481,271

Claims priority, application Great Britain Mar. 6, 1974

Term of patent 14 years

Int. Cl. D14—01

U.S. Cl. D26—14 D

FIG. 2.

FIG.1.

FIG. 3.

FIG.5.

FIG.8

FIG.6.

FIG.7

FIG. 1 is a side elevation of a record player pick-up cartridge showing my new design;

FIG. 2 is a front elevation thereof;

FIG. 3 is a rear elevation thereof;

FIG. 4 is a top plan view thereof;

FIG. 5 is a bottom plan view thereof;

FIG. 6 is a top front perspective view thereof;

FIG. 7 is a sectional view taken on line 7—7 of FIG. 4; and

FIG. 8 is a side elevation thereof from the side opposite that shown in FIG. 1.

I claim:

The ornamental design for a record player pick-up cartridge, substantially as shown.
